A. J. TANNER,
POCKETKNIFE AND THE LIKE,
APPLICATION FILED FEB. 11, 1920.

1,413,683.

Patented Apr. 25, 1922.

UNITED STATES PATENT OFFICE.

ARNOLD J. TANNER, OF NORTH HAVEN, CONNECTICUT.

POCKETKNIFE AND THE LIKE.

1,413,633.

Specification of Letters Patent. Patented Apr. 25, 1922.

Application filed February 11, 1920. Serial No. 357,902.

To all whom it may concern:

Be it known that I, ARNOLD J. TANNER, a citizen of the United States, and resident of North Haven, in the county of New Haven 5 and State of Connecticut, have invented certain new and useful Improvements in Pocketknives and the like, of which the following is a specification.

This invention relates to the manufacture 10 of pocket knives or like folding articles, and in part thereof, may be applied to the handles of certain other tools.

The purpose of the invention, amongst 15 other things, is to produce a durable and efficient article having the main parts thereof secured together, independently of the scales or covering plates for the handle. The same means however, which secure said main parts, also secure said covering plates, 20 and to improve the appearance of the knife handle, and to strengthen the construction, said means are embedded and concealed in said covering plates. The invention furthermore, facilitates manufacture whereby cost 25 of production is materially reduced.

In carrying out an embodiment of the invention, as applied to a folding or pocket-knife, the latter has the usual handle portion composed preferably of framing or 30 cheek-plates, and the latter, with the covering plates, the blade or blades and the spring or springs therefor, are mounted and held together by the same rivets. The rivets employed herein, are provided with hollow, ex- 35 panded or flared ends or heads protruding from the outer surface of the framing plates, holding the parts of the knife firmly together and presenting an under-cut or inwardly tapering head at various points for 40 securing the covering plates.

It is essential, with the present invention, 45 that the aforesaid covering plates should be composed of a substance capable of being brought to a plastic state, or otherwise rendered pliable, for when in that state, the plates are pressed on the knife handle, completely covering the rivet heads and forcing substance of which the plates is composed, to flow around and under the rivet heads. 50 By this method and means, the rivet heads are concealed by being embedded in the plates and when hardened, naturally or by any suitable process, said plates cannot then be removed without breaking the same.

55 Furthermore, during the operation of pressing the covering plates, or artificially

hardening them, by a vulcanizing process for example, they may be molded into the required shape with a polish obtained by pressure or any design may be pressed 60 thereon.

The substance used in the composition of the covering plates may be any suitable known kind, but desirably the substance should be workable at a comparatively low 65 temperature, for instance as obtained with boiling water or wet steam, for it will be understood, the fixing of the covering plates is a final operation, after the handle and the finished blades are assembled, consequently, 70 if the covering plates are required to be fixed in a great heat, a deteriorating effect to the knife and blades might result, if particular care is not taken. Other substances, in a powdered form, plastic or pliable in a wet 75 state, or when subjected to heat of a determined temperature, may be used, but obviously, whatever composition is used, the covering plates must be impervious to moisture, when dried or hardened. Any sub- 80 stance employed must also be such that it will not soften in a comparatively low temperature, under say 150 degrees, which with reasonable use is a fairly high temperature.

Several embodiments of the invention, 85 utilizing the improved method of manufacture and the improved means associated therewith, are more fully described herein- after with reference to the accompanying drawings, wherein—

Figure 1 is a side elevation of a pocket- 90 knife having a single folding blade;

Figure 2 is a cross section taken on line 2—2 of Figure 1;

Figure 3 is a fragmentary longitudinal 95 section taken on line 3—3 of Figure 1;

Figure 4 is a cross section taken on line 4—4 of Figure 1;

Figure 5 is a sectional view illustrating one form of flask or mold whereby the cov- 100 ering plates are molded and pressed on the knife handle;

Figure 6 is a detail, enlarged sectional view, illustrating the form of rivet em- 105 ployed;

Figure 7 is an enlarged sectional view illustrating a modified form of rivet;

Figure 8 illustrates the invention as applied to a tool wherein the shank or ex- 110 tended tang of the tool provides the base of the handle, and

Figure 9 is a cross section illustrating the

invention as applied to a pocket-knife having two blades mounted on the same rivet.

Referring to the drawings, the knife handle is composed of the cheek or frame plates 1 in which the blades or blades 2 are pivotally mounted on rivet 3 so as to close into the handle. The spring or springs 4, for the blade or blades, are secured by rivets 5. The latter rivets, rivet 3 and rivet 6 in the 10 butt end of the handle, are alike and serve, besides their other functions, to hold the covering plates on the outside of the plates 1. The rivets are all hollow or tubular 15 and before insertion, in their original state, they may be constructed as shown in Figure 6, wherein one end is expanded or flared, by spinning or otherwise, to form the inwardly tapering, hollow head 8. After assembling the frame plates, blades, springs 20 and the rivets, the upper end of the rivets is then likewise expanded or flared, or should it be more convenient, both ends may be expanded at the same time. The heads 8 are left to protrude from the outer surfaces 25 faces of the plates 1, and around the tapering heads 8 an under-cut space 9 is formed.

The assembled knife, to which the covering plates 7 are to be added, is placed into a mold or former of a suitable press, such 30 as shown for example, in Figure 5. Herein the two members 10 and 11, guided by posts 12, are brought together when containing the knife, with the material for forming the covering plates, in the shape 35 of slabs 13. Dies 14, carried by the press members, may be employed to impress a design on the covering plates, or the surface of the recesses 15, in the members 10 and 11, may be polished whereby polish is applied 40 to the covering plates. The corners 16 of the recesses 15 are desirably rounded so as to give like form to the edges of the covering plates and to cover the edges of the framing plates when required.

45 The mold or flask illustrated herein, may be one of a series in the same press, and during the operation of molding and fixing the covering plates, the slabs 13, previously placed in their proper relative position to the plates 1, are subjected, preferably, to moist heat such as obtained with boiling water or wet steam, and when and while so rendered into a plastic or pliable state, the members 10 and 11, are pressed together, 55 forcing the material to flow around the rivet heads, completely filling the under-cut spaces 9. When the material of the covering plates has set or hardened by this or any other suitable process, the said plates 60 will be tightly and permanently held in place by the heads 8, which are embedded in the covering plates and thus totally concealed.

In Figure 8, the handle is applied by the 65 improved method and with the improved

rivet having the expanded, protruding head, but in this instance, the handle sections 17 and 18 completely cover the tang 19 of the tool. In this form, an additional and obvious advantage as regards safety from electric shock, is obtained if the handle is composed of an electric insulating material.

Figure 9 illustrates the invention as applied to a knife having two blades mounted on the same rivet. In such a construction, 75 two springs arranged side by side, are required and also the division plate 20 is employed. A knife of this description, is considerably thicker than a single bladed knife, therefore to improve the appearance, 80 amongst other things, of the back of the knife, the edges 21 of the plates 1 partially cover the springs 4, and the covering plates have their edges pressed over so as to cover said edges 21, thus besides giving a neater 85 appearance to the back of the knife, also strengthening the covering plates.

In some instances where the knife handle is of considerable length, it may be desirable to secure the covering plates at intermediate 90 points. A rivet through the handle would prevent operation of the blades, therefore the equivalent of the expanded hollow head 8 is provided, by drawing out the metal of the plates 1, to form hollow protuberances 95 22 which are perforated and flared as illustrated in Figure 4.

Furthermore, when the knife is comparatively large and likely to receive rough usage, to re-enforce the handle at the blade end, 100 the ends of the plates 1 are turned upwardly to form a guard 23.

A ring 24, by means of which the knife can be fastened to a chain, may conveniently be secured in the hollow rivet 6 at the butt end 105 of the knife.

In Figure 7 a modified form of rivet is shown, wherein the rivet shank 25 is solid, but is bored out at the ends 26, which ends, in the operation of securing the handle plates 110 1 and the blades, are flared to form the hollow heads 8, the edges of which are turned inwardly or crimped at 27, so as to constrict the opening of the cavity in the hollow head. In this construction, besides filling the under-cut space, which is not quite so pronounced, 115 the material of the covering plates, will be forced into the cavity of the head so as to fill the same, thus forming an integral tongue providing effectual securing means, 120 with or without the under-cut spaces 9. One advantage herewith, is that the covering plates in this instance, may be thinner than those of the other constructions above described.

The chief advantages of a knife or other article, constructed in accordance with the invention hereinbefore described, are that the rivets holding the handle together and securing the blades and springs, are firmly 130

held in the metal plates 1 instead of in the comparatively softer covering plates, as is the method generally adopted. Also the covering plates herein are firmly held by the 5 embedded and concealed hollow expanded rivet heads much better than by means of the ordinary and exposed rivet heads heretofore used.

I claim—

- 10 1. The method of manufacturing articles of the class described consisting in building up the handle portion thereof of sheet metal plates, uniting said plates by means of rivets having hollow and projecting ends, expanding said ends to form heads so as to hold 15 said plates together, and after said article is assembled, applying to the outer surfaces of said plates, a covering material under

pressure and when in a plastic state, so as to mold said material on said plates and embed said rivet heads in said material. 20

2. A method of manufacturing pocket or folding knives consisting in first assembling the parts of a knife comprising handle sections or plates, a pivoted blade or blades and a spring or springs; uniting and securing said parts by means of rivets having hollow ends which are expanded to form projecting heads; and molding on said handle sections or plates covering scales or plates in which said rivet heads are embedded and concealed. 25 30

Signed at North Haven, in the county of New Haven and State of Connecticut, this 10th day of February, A. D. 1920.

ARNOLD J. TANNER.
